United States Patent

Des. 237,434
Patented Nov. 4, 1975

237,434

BENCH

Robert C. Le May, Jr., 410 4th St.,
East Greenville, Pa. 18041

Filed Jan. 21, 1974, Ser. No. 434,930

Term of patent 14 years

Int. Cl. D6—01

U.S. Cl. D6—60

FIG. 1.

FIG. 2.

FIG. 3.

FIG. 4.

FIG. 5.

FIG. 6.

FIG. 7.

FIG. 8.

FIG. 1 is a perspective view of a bench embodying my new design taken from the front and right;

FIG. 2 is a left side view of the bench of FIG. 1;

FIG. 3 is a perspective view of the bench of FIG. 1 taken from the rear and right;

FIG. 4 is a top plan view of the bench of FIG. 1;

FIG. 5 is a perspective view of an alternate embodiment of the bench of FIG. 1 taken from the front and right;

FIG. 6 is a left side view of the bench of FIG. 5;

FIG. 7 is a perspective view of the bench of FIG. 5 taken from the rear and right; and

FIG. 8 is a top plan view of the bench of FIG. 5.

I claim:

The ornamental design for a bench, as shown.
